UNITED STATES PATENT OFFICE.

GEORGE BAILEY, OF SHELTON, CONNECTICUT, ASSIGNOR TO ROBERT N. BASSETT COMPANY, INCORPORATED, OF SHELTON, CONNECTICUT, A CORPORATION OF CONNECTICUT.

SUITCASE-HASP.

1,229,207.

Specification of Letters Patent. Patented June 12, 1917.

Application filed September 21, 1916. Serial No. 121,369.

To all whom it may concern:

Be it known that I, GEORGE BAILEY, a citizen of the United States, residing at Shelton, in the county of Fairfield and State of 5 Connecticut, have invented a certain new and useful Improvement in Suitcase-Hasps, of which the following is a specification.

My invention relates to spring hasps for suit cases, trunks and like articles and its 10 object is to provide a hasp in which the spring can be slipped into its seat by hand after the other parts have been assembled.

I attain this and other objects of my invention in the device set forth in the following description and accompanying drawings in which like reference characters refer to corresponding parts.

In the drawings:

Figure 1, is a front view of the hasp;

20 Fig. 2, a rear view;

Fig. 3, an enlarged longitudinal sectional view taken on line $x-x$ in Fig. 1, and

Fig. 4, an enlarged transverse sectional view taken on line $y-y$ in Fig. 2.

25 The device generally comprises a face plate A, a hasp plate B, a retaining plate C, a spring D, and a stud or button E. The hasp plate B is countersunk from a body portion 2, and an inwardly projecting flange 3 around its edges. A pair of lugs 4, 4 project from the top edge of this flange and the lugs 5, 5 project respectively from its side edges. The face plate A is likewise countersunk to form a body portion 6 and an inwardly projecting peripheral flange 7. The body portion 6 is provided with apertures 8, 8 to permit the passage of rivets in attaching the same to the suit case, trunk or like article on which the hasp is used. The 35 middle of the body portion 6, is provided with a rectangular recess 9 opening downwardly. The metal along the opposite sides of this recess is depressed outwardly to form raised portions 10, 10.

40 The hasp plate B is connected to swing to and from the face plate A by inserting the lugs 5, 5 under the raised edges 10, 10 and the lugs 4, 4 under the top edge 11 of the recess 9. The depressions formed by the 45 raised edges 10, 10 are bridged by a back, or retaining plate C, which is suitably riveted to the back of the body portion 6. The retaining plate C is recessed in back of the lugs 4, 4 and the lower edges 12, 12 of these 50 recesses are depressed under these lugs to

hold them in position in back of the top edge 11 of the recess 9 in the face plate. Extending downwardly between the edges 12, 12 is another recess having parallel side edges 13, 13. The hasp plate B is normally held 60 outwardly at an angle to the face plate by the flat sheet metal spring D which passes through the retaining plate, between the edges 13, 13 and under the bottom edge 14. This spring is suitably bent so that its 65 flanged upper extremity 15 overlaps the top edge 16 of the retaining plate and its lower extremity 17 slidably engages the body portion 2 of the hasp plate. In assembling the parts, the hasp plate B is inserted in the 70 recess 9 of the face plate A so that the lugs 4, 4 project under the top edge 11 and the lugs 5, 5 project under the depressed side edges 10, 10. The back plate C is then riveted to the body portion 6 of the face 75 plate so that the depressed edges 12, 12 are disposed immediately below the lugs 4, 4 and the side edges 13, 13 are disposed in back of and between the depressed edges 10, 10 of the face plate. The hasp plate B is thus 80 retained in place by the back plate so that the lugs 4, 4 are confined between the edges 11 and 12, 12 thereby forming a hinge or pivotal connection.

The swinging movement or throw of the 85 hasp plate is limited by the lugs 5, 5 which are confined in the pockets formed between the depressed edges 10, 10 and the retaining plate. My invention is not confined to this particular construction of pivoted hasp plate 90 but resides in the manner of mounting the spring which will now be described. The spring D, is passed forwardly and downwardly through the back plate between the edges 13, 13 until its forward extremity 17 95 bears against the hasp plate. The elbow 18 of the spring is then pressed forwardly and downwardly until it slips under and beyond the lower edge 14 of the back plate. At the same time the flanged extremity 15 of the 100 spring rides over the back edge of the flange 7 on the face plate and becomes seated against the top edge 16 of the back plate, and the opposite extremity 17 slides along the body portion 2 of the hasp plate to a position in proximity to the stud E. The spring thus seated normally holds the hasp plate in its outward or forward position, as shown in Fig. 3, and is fulcrumed against the lower edge 14 of the back plate when flexed by the 105 110

inward or rearward swing of the hasp plate. In this manner the spring may be slipped into its seat by hand after the other parts of the hasp have been riveted together.

5 While the hasp above described is the preferred embodiment of my invention it is susceptible to such modification as may fairly come within the scope of the appended claims.

10 Having now described my invention what I claim and desire to protect by Letters Patent is:

15 1. A device of the character described comprising rigidly connected front and back members, a hasp plate pivotally connected to one of said members, a stud projecting from said hasp plate and a sheet metal spring removably seated against one of said members, the said spring being arranged to slidably 20 engage said hasp plate in proximity to said stud.

2. In a device of the character described

rigidly connected front and back members, a hasp plate pivotally connected to one of said members and a sheet metal spring provided with a retaining flange which is seated against a shoulder on one of said members, the said spring being arranged to slidably engage said hasp plate.

25 3. A hasp for suit cases and like articles comprising rigidly connected front and back members, a hasp plate pivoted to said front member, a stud mounted on said hasp plate, the said back member being provided with an opening, and a flat spring passed through said opening, the said spring having one of its extremities seated against one of said members beyond said opening and its opposite extremity slidably engaging said hasp plate in proximity to said stud.

30 40 In testimony whereof I have hereunto set my hand this 30th day of August, 1916.

GEORGE BAILEY.
